UNITED STATES PATENT OFFICE.

JOSEPH LUCCINO, OF BROOKLYN, NEW YORK.

DAVENPORT SOFA-BED.

1,269,630.

Specification of Letters Patent. Patented June 18, 1918.

Application filed September 15, 1915. Serial No. 50,807.

To all whom it may concern:

Be it known that I, JOSEPH LUCCINO, a citizen of the United States, and a resident of the borough of Brooklyn, city and State of New York, have invented certain new and useful Improvements in Davenport Sofa-Beds, of which the following is a specification.

My invention relates to folding beds, and has for some of its principal objects to provide such a bed which shall be easily opened or closed, which may be closed with the mattress in place, which when closed will occupy a small space, and which may be used as a davenport sofa.

The invention consists in the novel construction, arrangement and combination of various devices, elements and parts, as shown in the accompanying drawings and fully described in this specification.

In the said drawings, Figure 1 is a perspective view of my improved davenport sofa bed, as it appears when in its closed position; Fig. 2 is a view, on an enlarged scale, of a detail to be hereinafter described; Fig. 3 is a view of my bed in its opened position, the mattress being removed; Figs. 4, 5 and 6 are sectional views showing various steps in the operation of closing the bed, the mattress being in place; and Fig. 7 is a sectional view of the same completely closed, with the mattress in place.

In carrying my invention into effect in the embodiment thereof which I have selected for illustration in the accompanying drawings, and description in this specification, I provide a davenport sofa frame comprising a rear portion having a top cross piece 15, side portions 12, and arms 23. I provide a back cushion 13, swingingly secured to the under side of the member 15, and a seat cushion 14, secured in a manner to be hereinafter described, these cushions being suitably covered.

As shown particularly in Fig. 2 each end of the cushion 13 is pivoted at 16 to a member 17, secured at 18 to the under side of the top cross-piece 15. A bracket 19 is rigidly attached at one corner of the cushion 13, which bracket carries a swinging link 20, having its lower end notched as shown at 21 in Fig. 3. The cushion 13 may be swung into the position shown by the dotted lines in Fig. 3, in which position the notch 21 will engage with a stop 22 on the inside

of the sofa frame. The cushion will be maintained in its elevated position until the notch 21 is released from the stop 22.

I provide a metal frame for the bed-portion, constructed as follows:

A member 23' extends across the back of the sofa frame at the bottom thereof, from which extend forwardly two members 24 at each side of the sofa frame. At the front end of each member 24 I provide an upright 25, secured by braces 26 and 27, the braces 26 being attached to the members 24, and the braces 27 being attached to a member 28, which member 28 forms the lower front portion of the sofa frame.

Pivoted to, and extending backward from, the top of the uprights 25 at the point 55, are angle-irons 29, having rigidly attached thereto at their rear ends a head-board 30, which also serves as a retaining bracket as hereinafter described. A member 31 is rigidly attached to each angle-iron 29 and extends downwardly therefrom. To the lower end of each member 31 is pivoted a link 32, to the other end of which is attached one end of a spring 33, the other end of the spring being attached to one end of the member 23. It will thus be seen that the action of the springs 33 will tend to prevent the head-board 30 or bracket 31 from dropping downward when the frame is folded as hereinafter described.

Also pivoted to the uprights 25 at 55 are angle-irons 34, which extend in a direction opposite to that of the angle-irons 29. A portion of each of these members 34 extends under the corresponding member 29 and beyond the pivotal point 55, as shown at 50 in order that the outer end of the member 29 may not swing downward. Rigidly attached to each member 34 is a leg 35. Each iron 34 bears a stud 36, to which is connected a slotted link 37, the lower end of which is pivoted to the rear side of the cushion 14. The front edge of the seat cushion 14 is secured to a member 38, which forms the upper front portion of the sofa frame. The members 28 and 38 are hinged together at 39.

I further provide angle-irons 40, pivotally secured to the tops of the members 35, at 54 and extending therefrom in a direction opposite to the irons 34. A portion of one end of each of the irons 34 extends under the

ends of each of the irons 40, as shown at 48, in order to prevent the outer end of the irons 40 from ever swinging downward.

Pivoted to the outer ends of 5 the irons 40, at 53 are angle-irons 41, having rigidly secured thereto at their outer ends a foot-board 42. Legs 43 are pivoted to the irons 41 at 44, the upper ends of these legs being pivoted at 45 to links 46 having their 10 other ends pivoted to the members 40 at 47. One end of each of the irons 41 extends under the end of the corresponding iron 40, as shown at 49, in order to prevent the outer end of the irons 41 from 15 swinging downward.

Suitable cross-pieces 51 are provided, in order to brace the longitudinal angle-irons forming the bed-frame, and also suitable means for supporting the mattress 52, such 20 means being shown in part in Fig. 3 and designated 70.

The operation of my invention is as follows:

The bed being in the position shown in 25 Fig. 3, it is supported on the legs 43, the legs 35, and the sofa frame, the longitudinal frame members of the bed, (the angle irons 29, 34, 40 and 41) being maintained in a horizontal position by the various pivots which connect them with the legs and with each other, (44, 53, 54, and 55) and by the projecting ends of these irons, (48, 49 and 50).

Assuming that the bed is in the position 35 shown in Fig. 3, and that it is desired to close the same, the bracket 30 is first raised into the position shown by the dotted lines in Fig. 4, the back cushion 13 raised into the position shown by the dotted lines in 40 Fig. 3, and secured by means of the rod 20, and the bracket 30 then allowed to resume its former position. It is necessary that the cushion 13 be temporarily raised, in order to provide room for the operation 45 of folding up the bed, and it is impossible to raise the cushion 13 unless the bracket 30 be first temporarily moved out of the way.

The next step is to raise the foot-board 50 42, swinging it and the irons 41 about the pivot 53 until they assume the position shown in Fig. 4. The leg 43 is automatically swung parallel with the iron 41 by the action of the link 46, and the irons 40, 55 although deprived of the support of the legs 43 and projections 49, will still remain in a horizontal position, being held by the projections 48.

In the next step the irons 40 and 41 retain 60 their relative positions, but both are swung around the pivots 54, and assume the position shown in Fig. 5.

The irons 34 are then raised into a vertical position, and the bed assumes the position 65 shown in Fig. 6. The irons 34, 40, and

41 retain their relative positions, the leg 35 extends horizontally, and the cushion 14 is held vertically in front of the partially closed bed by means of the slotted link 37.

The parts are now allowed to fall into 70 the position shown in Fig. 7, (which is drawn to an enlarged scale) in which the bed is completely closed, and the cushion 14 drawn into a horizontal position between the arms of the sofa frame, and supported on the irons 34. It will be observed that the stud 36 no longer occupies the end of the slot in the link 37. The legs 35 extend upward at the rear of the sofa frame, out of sight behind the cushion 13, which 80 is then lowered. It will be observed that when in this position the section bearing the footboard is supported by the bracket 30, which extends horizontally toward the rear of the sofa. 85

It will be observed that the parts can only be lowered into the position shown in Fig. 7 against the tension of the spring 33. This spring tends to prevent the folded bed from falling into position too suddenly, 90 and also assists by its tension in the initial step in unfolding the bed, which consists in moving the parts into the position shown in Fig. 3.

Having fully described the operation of 95 closing the bed, the operation of opening it, which is exactly the reverse of this will be readily understood. When the bed is in its opened position the bracket 30 serves as the head-board.

The advantages of my invention will be obvious from what has been above set forth concerning its construction and mode of operation.

I do not limit myself to the exact form 105 described and shown, as it will be obvious that various modifications may be made without departing from the spirit and scope of my invention.

Having thus described my invention, 110 what I claim as new and desire to secure by Letters Patent is as follows:

1. In a davenport sofa bed, the combination with a stationary frame; of a movable sectional frame adapted to be folded up inside said stationary frame by folding over the sections of said movable frame successively all in the same direction, the folded movable frame being then rotated inside said stationary frame through an angle of 115 approximately ninety degrees, one of said sections being provided with a bracket adapted, when said movable frame is so folded and rotated, to extend horizontally from said section and to support another of 120 said sections.

2. In a davenport sofa bed, the combination with a stationary frame; of a movable sectional frame adapted to be folded up inside said stationary frame by folding over 125

the sections of said movable frame successively all in the same direction, the folded movable frame being then rotated inside said stationary frame through an angle of approximately ninety degrees, one of said sections being provided with a rigidly attached bracket adapted, when said movable frame is so folded up and rotated, to extend horizontally from said section and to support another of said sections.

3. In a davenport sofa bed, the combination with a stationary frame provided with a pair of uprights; of a movable sectional frame adapted to be folded up inside said stationary frame by folding over the sections of said movable frame successively all in the same direction, the folding movable frame being then rotated inside said stationary frame through an angle of approximately ninety degrees, said movable frame comprising a bed member pivotally secured to said uprights, said bed member bearing a bracket adapted, when said movable frame is so folded up and rotated, to extend horizontally from said section and to support another bed member, a second bed-member pivotally secured to said uprights and bearing a support, a third bed member pivotally secured to said second bed member, and a fourth bed member pivotally secured to said third bed member and bearing a support.

4. In a davenport sofa bed, the combination with a stationary frame provided with a pair of uprights; of a movable sectional frame adapted to be folded up inside said stationary frame by folding over the sections of said movable frame successively all in the same direction, the folding movable frame being then rotated inside said stationary frame through an angle of approximately ninety degrees, said movable frame comprising a bed member pivotally secured to said uprights, said bed member bearing a bracket rigidly attached thereto and adapted, to extend horizontally therefrom and to support another bed member when said movable frame is so folded up and rotated, a second bed member pivotally secured to said uprights bearing a support, a third bed member pivotally secured to said second bed member, and a fourth bed member pivotally secured to said third bed member and bearing a support.

5. In a davenport sofa bed, the combination with a stationary frame provided with a pair of uprights; of a movable frame comprising a bed-member pivotally secured to said uprights and bearing a head board, a second bed-member pivotally secured to

said uprights and bearing a support, a slotted link suspended from said second bed-member, a seat member swingingly secured to said stationary frame and pivotally secured to said link, a third bed-member pivotally secured to said second bed-member, and a fourth bed-member pivotally secured to said third bed-member and bearing a foot board and a support; said movable frame being adapted to be folded up inside said stationary frame by folding over the sections of said movable frame successively all in the same direction, the folding movable frame being then rotated inside said stationary frame through an angle of approximately ninety degrees.

6. In a davenport sofa bed, the combination with a stationary frame provided with a pair of uprights, of a movable frame comprising a bed member pivotally secured to said uprights, a second bed-member pivotally secured to said uprights and bearing a support, a third bed-member pivotally secured to said second bed-member, a fourth bed-member pivotally secured to said third bed-member and bearing a foot-board and a support; said movable frame being adapted to be folded up inside said stationary frame by folding over the sections of said movable frame successively all in the same direction, the folding movable frame being then rotated inside said stationary frame through an angle of approximately ninety degrees; and a seat member swingingly secured to said stationary frame and connected with said movable frame by means of a slotted link.

7. In a davenport sofa bed, the combination with a stationary frame provided with a pair of uprights, of a movable frame comprising a bed-member pivotally secured to said uprights, a second bed-member pivotally secured to said uprights and bearing a support, a third bed-member pivotally secured in said second bed-member, a fourth bed-member pivotally secured to said third bed-member and bearing a support; said movable frame being adapted to be folded up inside said stationary frame by folding over the sections of said movable frame successively all in the same direction, the folding movable frame being then rotated inside said stationary frame through an angle of approximately ninety degrees; and a seat member swingingly secured to said stationary frame and connected with said movable frame by means of a slotted link.

In witness whereof I have hereunto signed my name this 31st day of August, 1915.

JOSEPH LUPPINO.
